UNITED STATES PATENT OFFICE.

LOUIS H. BRINKMAN, OF GLEN RIDGE, NEW JERSEY.

TUBE-BENDING MACHINE.

1,309,238.

Specification of Letters Patent.

Patented July 8, 1919.

Application filed November 27, 1918. Serial No. 264,324.

To all whom it may concern:

Be it known that I, Louis H. BRINKMAN, a citizen of the United States, residing in the borough of Glen Ridge, in the county 5 of Essex and State of New Jersey, have invented certain new and useful Improvements in Tube-Bending Machines, of which the following is a full, clear, and exact description, such as will enable others skilled 10 in the art to which it pertains to make, construct, and use the same, reference being had to the accompanying drawings, and to numerals of reference marked thereon, forming a part of this specification.

15 This invention relates to machinery for bending tubing, and more especially for the bending of metal pipes or tubes.

20 The object of the invention is to provide a simple and automatic machine of this character, which shall in a thoroughly, practical and efficient manner, bend metal pipes or tubes and to prevent disfiguration of the tubing in bending.

25 Further objects of the invention are to simplify the general construction and operation of the machine, cheapen the cost thereof, and to facilitate the operation.

30 The construction and operation of my machine will be more fully described in the specification which follows, and in the accompanying drawings which form a part thereof wherein I have shown a preferred embodiment of my device in a machine especially adapted for the bending of metal pipes 35 or tubes.

Throughout the specification and drawings like reference numerals are employed to indicate corresponding parts in the drawings, wherein—

40 Figure 1 represents a plan view of a machine embodying my invention.

Fig. 2 represents the embodiments illustrated in Fig. 1, with the bending members in position after the desired bend has been 45 completed.

Fig. 3 represents a side elevation of the machine.

Fig. 4 represents a sectional plan view taken on line $x-x$ of Fig. 3.

50 Fig. 5 represents a reduced perspective view of the lower turn table, and

Fig. 6 represents a fragmentary, enlarged, sectional side elevation of the upper and

lower turn tables and tube bending members, taken on line $x-x$ of Fig. 2, looking 55 in the direction indicated by the arrow.

Referring to the drawings, 1 represents the base, mounted upon suitable supports 2, for supporting the mechanism for bending tube. At 3 is shown a support of whatever 60 character desired, which may be secured to the supports 2, in any suitable manner and upon which is mounted a vertical shaft 4, near the lower end of which a gear wheel 5 is secured, the teeth of which engage with 65 a worm gear 6 mounted upon the horizontal drive shaft 7. Rigidly secured to the upper or opposite end of the vertical shaft 4 by any suitable means is a turn table 8 designed to be rotated by the vertical shaft 4. A reciprocating member 9 is slidably arranged 70 in suitable guide ways 10 formed on the underside of the base 1 of the machine. (See Fig. 4 of the drawings.) The reciprocating member 9 has secured thereto, in any 75 desired or convenient manner, two pivotally arranged spring-actuated bell-cranks 11 and 12, designed to be engaged by the cams 13 and 14 which are rigidly secured to the vertical shaft 4 and by means of the rotation 80 of said shaft and the engagement of the cams with the ends of said cranks a reciprocating movement is imparted to the member 9. In order to limit the forward and rearward movement of the reciprocating 85 member 9, suitable studs 15 and 16 are arranged upon the underside of the base 1, with which the opposite ends of the bell-cranks engage. One end of the reciprocating member 9 is provided with an upwardly 90 and transversely arranged support 17, to which one end of a mandrel 18 is adjustably secured. The mandrel may be of any suitable form and shape whereby bending can be correctly and easily performed.

At 19 is shown a movable support into which is fitted a removable pipe supporting jaw 20. The support 19 together with said supporting jaw which it carries, is so arranged as to be moved toward the mandrel 100 or swung clear of the same in the following manner:—

Pivotedly arranged upon said support 19, at 21, is one end of a link 22, the other end of which is pivotally secured to a bracket 23 105 secured to the support 17; and also pivotally

secured to the support 19 as at 24, is another link 25, which is adjustably connected with a link 26 pivotally secured at 27 to a bracket 28, which is secured to the side of the base 1 of the machine. The bracket 28 preferably is provided with a series of studs 29 to be engaged by the link 26 in order to vary the range of adjustment of the links 25 and 26.

Loosely and rotatively mounted upon the 10 lower turn table 8 is the upper turn table 30 to which is rigidly secured a tube bending member 31, preferably having a curved surface of whatever character desired. Secured to the top of the tube bending member 31, by means of bolts 32 is a bracket 33 for the reception of an adjustable and removable pipe clamping jaw 34, designed to be removed from the bracket 33 when the tube 35 is to be inserted or removed. The 15 tube bending member 31 and the pipe supporting jaw 20 and the clamping jaw 34 are provided with grooves of such contour that the tube is tightly supported and gripped between the supporting jaw 20 and the 20 clamping jaw 34. In the form shown the grooves in the jaws 20 and 34 as well as in the tube bending member 31 would, of course, be semi-cylindrical in cross section. Any 25 suitable means, such as a clamping screw 36, provided with a handle 37, is provided for clamping the pipe between the tube bending member 31 and clamping jaw 34.

The upper turn table 30, as previously 30 stated, is loosely and rotatively mounted 35 upon the lower turn table 8, in such a manner that during the bending of the pipe the two tables are locked together so as to rotate in unison during the bending of the pipe. After the bend has been made the upper table is unlocked from the lower one in 40 order to bring the upper table back into the position illustrated in Fig. 1 of the drawings, preparatory to inserting another pipe and bending the same. As illustrated in the 45 drawings, the upper turn table 30 along its peripheral surface is provided with two recessed or cut-away portions, numbered respectively, 38 and 39. The recess 38 is covered by an overlying adjustable cover-plate 50 40, provided with an extension 41, and the recess 39 is covered by an overlying cover-plate 42. The adjustable cover-plate 40 is provided with a pair of slots 43 through 55 which bolts 44 pass and by means of which said cover-plate 41 is adjustably secured to the top of the turn table 30. Similar bolts 45 are employed for securing the cover-plate 42 to the top of the table. Carried by and 60 pivotally secured to the underside of each of said cover-plates, and located within the recesses 38 and 39 of the turn table 30, in any desired or convenient manner, are the spring actuated latches 46 and 47.

The spring actuated latch 46 is designed to

have holding engagement with a stud 48, located on the top of the base 1 of the machine, when the turn table 30 is in the position indicated in Fig. 1 of the drawings, preparatory to making a bend, and the spring actuated latch 47 is designed to have holding engagement with a stud 49 located on the top of the base 1 of the machine, when the turn table 30 is in the position indicated in Fig. 2 of the drawings, after the desired bend has been completed.

Carried by and pivotally secured to the underside of the extension 41 of the adjustable cover-plate 40, in any desired or convenient manner, is a spring actuated break-hinge latch 50, the front or free end 80 of which is designed to engage with a recess 51 formed in the peripheral surface of the lower turn table, 8, (see Figs. 1 and 5) with which it has holding engagement in order to lock the upper and lower turn tables together and keep them locked until the desired bend has been completed. The turn table 30 is again brought into the position illustrated in Fig. 1 of the drawings (after the bent tube has been removed), by simply 90 releasing the spring actuated latch 47 from the stud 49 by means of a handle 52 secured to said latch in any desired or convenient manner.

The main or horizontal drive shaft 7, 95 which carries the worm gear 6, is mounted in suitable bearings 53, and has secured to one end thereof, a drive pulley 54, and in close proximity thereto a clutch 55 connected with a shifting bar 56, which is operatively connected with the operating lever 57 of the machine. Means are provided for automatically stopping the machine when the bend has been completed. Said means consisting of a spring actuated pawl 58 conveniently secured upon the upper surface of the gear wheel 5, designed to engage with a stop 59, secured to the shifting bar 56, thereby disengaging the clutch 55 from the pulley.

The operation of my device will be apparent from the description. Assuming the parts to be in the position indicated in Fig. 4 of the drawings, rotation of the gear wheel 5 will cause the cam 13, which engages with the crank 11, to move the reciprocating member 9 into the position indicated in Fig. 1 of the drawings, during which operation the free end of the crank 11 has engaged with the stud 15 arranged upon the underside of the base 1, and the cam 13 has become disengaged from the crank 11, and further forward movement of the reciprocating member 9 ceases. The parts, as illustrated in Fig. 1 of the drawings, are now 125 ready to receive the pipe preparatory to making the bend. Further rotation of the gear wheel 5 causes the cam 14 to engage

with the crank 12 which causes the reciprocating member 9 to be moved in the opposite direction, until the free end of the crank 12 engages with the stud 16, which is also arranged upon the underside of the base 1 and which limits the forward movement of the reciprocating member, during which movement the bend is made in the following manner:

- 10 The parts, now being in the position illustrated in Fig. 1 of the drawings, are caused to assume the position indicated in Fig. 2 of the drawings, by reason of the further rotation of the gear wheel 5 and the forward movement of the reciprocating member 9, which moves the mandrel 18 and the movable support 19, carrying the pipe supporting jaw 20, into the position illustrated in Fig. 2 of the drawings.
- 20 Further rotation of the gear wheel 5 rotates the lower turn table 8, which is keyed to the vertical drive shaft 4, and during the rotation of said turn table 8 the plate 60, which is set into the peripheral surface of the turn table 8, (see Fig. 5 of the drawings) engages with the spring actuated latch 46 thereby releasing it from the stud 48, and simultaneously causes the front or free end of the break-hinge latch 50 to engage with the recess 51 formed in the peripheral surface of the lower turn table, thereby locking the upper and lower turn tables so that they will rotate together only until the desired bend has been completed which, in this case, 35 takes place when the said break hinge latch 50 engages with the stud 49 located on the top of the base of the machine.

It will also be noted that, when the spring actuated latch 47 has holding engagement 40 with the said stud 49, then the desired bend has been completed. When the bend has been completed and the break-hinge latch engages with the stud 49, the free end of the latch becomes disengaged from the lower 45 turn table 8 and the upper turn table 30 is in that manner unlocked from the lower turn table, in order that the lower turn table can rotate without carrying the upper turn table with it. Further rotation of the gear wheel 5 causes the reciprocating member, together with the mandrel and the movable support carrying the supporting jaw 20, to be moved in the position indicated in Fig. 1 of the drawings, and by releasing the latch 47 55 from the stud 49, by means of the handle 52, the upper turn table 30 can be swung into the position illustrated in Fig. 1 of the drawings, in order to make another bend.

Experience has demonstrated that the 60 organization above described is a highly efficient one, and while I have shown the preferred embodiment of my present invention, I do not wish to be limited to the exact details of construction shown and described, 65 as obvious modifications thereof, not involv-

ing the exercise of invention, may be made by any skilled mechanic, and such departures from what is herein set forth, I consider within the scope and terms of my claims.

Having thus described my invention, what 70 I desire to obtain by Letters Patent is:—

1. In a tube bending machine, the combination of a base, a lower turn table rotatively mounted upon said base, means for rotating said lower turn table, an upper turn 75 table mounted upon the said lower turn table, a bending member and adjustable pipe clamping means rigidly secured to the upper turn table, a reciprocating member slidably secured to the base of the machine, a mandrel and adjustable pipe supporting means carried by said reciprocating member and base, means for imparting a reciprocating movement to said reciprocating member thereby imparting to said mandrel and adjustable pipe supporting means a movement 80 toward and away from said pipe bending member carried by the upper turn table, and means carried by the upper turn table designed to engage with means on the lower 85 turn table for automatically and rotatively locking and unlocking the two tables.

2. In a tube bending machine, the combination of a base, a lower turn table mounted upon said base, means for rotating said 90 lower turn table, an upper turn table mounted upon the said lower turn table, a bending member and adjustable pipe clamping means carried by the upper turn table, and means carried by the upper turn table 95 designed to have locking engagement with the lower turn table for automatically and intermittently locking and rotating the upper turn table with the lower turn table.

3. In a tube bending machine, the combination of a base, a lower turn table mounted upon said base, means for rotating said lower turn table, an upper turn table mounted upon the said lower turn table, a bending member and adjustable pipe clamping means carried by the upper turn table, means carried by the upper turn table 100 designed to have locking engagement with the lower turn table for automatically and intermittently locking and rotating the upper turn table with the lower turn table, a reciprocating member slidably secured to the base of the machine, a mandrel and adjustable pipe supporting means carried by said reciprocating member and base, means for 105 imparting a reciprocating movement to said reciprocating member, and means located on the base of the machine for limiting the movement of said reciprocating member.

4. In a tube bending machine, the combination of the driven tube bending and positioning mechanism, comprising upper and lower turn tables operatively connected, means for automatically and intermittently locking, unlocking and rotating said mecha- 110 115 120 125 130

nism, a reciprocating mandrel, and means for automatically reciprocating and limiting the movement of said mandrel.

5. In a tube bending machine, the combination of a base, a lower and an upper turn table operatively connected and mounted upon the top of said base, means for rotating the lower turn table, means for automatically and intermittently locking and rotating the upper turn table, a mandrel and adjustable pipe supporting means, and means for automatically moving said mandrel and adjustable pipe supporting means out of the way to permit the removal of the tube.
10. In a tube bending machine, the combination of a base, a lower and an upper turn table operatively connected and mounted upon the top of said base, means for rotating the lower turn table, means for automatically and intermittently locking and rotating the upper turn table, a mandrel and adjustable pipe supporting means, and means for automatically moving said mandrel and adjustable pipe supporting means toward and away from said pipe bending member.

15. In a tube bending machine, the combination of intermittently driven tube bending and positioning mechanism comprising a driven turn table secured to which are pipe bending and clamping members, a reciprocating mandrel and adjustable pipe supporting means, and means for automatically moving said mandrel and adjustable pipe supporting means toward and away from said pipe bending member.

20. This specification signed and witnessed this 26th day of November, 1918.

LOUIS H. BRINKMAN.
